UNITED STATES PATENT OFFICE

PIERRE LEONCE GARDÈRE, OF BORDEAUX, FRANCE

POWER TRANSMITTING BELT

Application filed September 9, 1927, Serial No. 218,552, and in France September 20, 1926.

The present invention relates to power transmitting belts of the type in which leather strips are laced in apertures of the belt.

5 The invention has for its object to provide a belt of this type, which will have a greater adherence than the belts heretofore used, which may be used on both faces and, for a given thickness and width, will afford a 10 greater resistance than the apertured belts with lacings of the prior art.

The invention will be clearly understood with reference to the appended drawing, which shows, by way of example, various 15 embodiments of the invention.

Fig. 1 shows a belt according to the invention.

Fig. 2 is a section on the line B—B of Fig. 1.

20 Fig. 3 shows a modification in which the design formed by the lacing comprises a row of chevrons.

Figs. 4 to 8 are diagrammatic views showing various combinations which may be obtained with inclined lines and chevrons.

25 In the constructional form shown in Figs. 1 and 2, the belt 1, which may have any suitable width and thickness and may consist of leather or like material of which belts are usually manufactured, is provided with two parallel rows of apertures 2, 2^a, 2^b, etc., 3, 3^a, 3^b, etc., which are either circular holes or preferably elongated slots and are equally spaced apart. In the said holes or slots are laced continuous strips 4, 5, etc., of leather, hemp or any other suitable material.

30 The width of the strips 4 and 5 is substantially equal to the length of the slots 2 and 3, and the thickness is equal to or somewhat above the width of the said slots. The lacing is performed in the following manner. The strip 4 is inserted from back to front through the slot 2 (Fig. 1) and then from front to back through the slot 3^a, then from back to front through the slot 2^b, and so on; the second strip 4 is laced in a similar manner through the slots 3, 2^a, 3^b and so on.

35 It will be observed at the lower part of Fig. 1 that the lacing of the said strips will form on the belt two sets of lines which are

inclined in inverse directions on the front and rear sides of the belt, with reference to the axis of the belt.

In Fig. 3, the lacing forms a design consisting of a series of chevrons. For this purpose I form on the axis of the belt a row of slots 6 whose width is substantially equal to twice the thickness of a strip. On either side of this row of slots I form rows of slots 7 each slot being on the same transverse axis as the corresponding slot 6, the width of the slots 7 being practically equal to the thickness of a strip. The figure clearly shows the manner in which the lacing the strips 8 and 9 is effected in this case.

Fig. 4 illustrates a modification of the lacing shown in Fig. 1, in which only a single strip 10 is utilized, and herein the spacing between the lines of the design formed by the lacing is greater than in the case of Fig. 1, assuming that the inclination of said lines upon the axis of the belt is the same.

Fig. 5 shows a belt comprising the combination of two lacings such as shown in Fig. 1, the design consisting of two sets of lines which are inversely inclined upon the axis of the belt.

Fig. 6 shows the combination of the lacing shown in Fig. 1, formed at the central part of the belt, with two sets of chevrons of the type represented in Fig. 3.

Fig. 7 shows a lacing which comprises two sets of chevrons whose vertices are directed in a direction and a set of chevrons at the central part, whose vertices have the contrary direction.

Fig. 8 is a modification of Fig. 1 in which the middle axis *a*—*a* of the lacing of the strip 5 does not coincide with the middle axis *b*—*b* of the lacing of the strip 4. In this particular case, the width and the spacing of the strips may be such that the edges of the said strips are in contact.

The arrangement of belting herein specified offers the following advantages:

Due to the inclined disposition of the lacing with respect to the belt axis, the belt will adhere more strongly to the pulleys, and the slipping of the belt will thus be reduced. The adherence to the pulley will be uniform

throughout the width of the belt. Moreover, the belt will have no back side and either face may be mounted in contact with the pulleys since the same face of the leather strips 5 (either the flesh-side or the grain-side) is at the exterior throughout the belt and on both sides thereof. Also, it will be noted that the width of the apertures need not exceed the thickness of the strips, which is com- 10 paratively small, whereas the width of the apertures in the known belts, provided with lacings extending longitudinally, must be substantially equal to the width of the strips.

By the use of a lacing which forms a de- 15 sign consisting of lines which are inversely inclined, the belt will have a tendency to remain in the proper direction of motion.

Obviously, the constructional forms shown in the drawing are susceptible of numerous 20 modifications without departing from the principle of the invention. For instance, I may superpose and connect together a cer- 25 tain number of belts of the kind described, or may combine a belt of this kind with an ordinary smooth belt.

Having now described my invention, what I claim as new and desire to secure by Letters Patent is:

1. A power transmitting belt comprising a 30 tension resisting core pierced with apertures disposed in at least two longitudinal rows, said apertures being symmetrically disposed with respect to the axis of that part of the belt comprised between said two longitudinal 35 rows and at least two strips of yielding material laced entirely around the belt through said apertures, the lacing being performed by continuously winding in an helical manner and in the same direction, each of said strips 40

around the longitudinal portion of core com- 76 prised between two adjacent rows of apertures and passing each strip through each second aperture of the same row, so that the same face of the strip, either the flesh-side or the grain-side is at the exterior throughout the belt and on both sides thereof.

2. A power transmitting belt of the type comprising a tension resisting core having at least two longitudinal rows of apertures 75 and at least one strip of yielding material laced entirely around the belt through said apertures, wherein the core is made of a single strap and the strip coiled around the longitudinal portion of core located between said rows of apertures by being alternately passed from one row to the other and then back to the first, so that the same face of the strip, either the flesh-side or the grain-side is at the exterior throughout the belt and on both sides 80 thereof.

3. A power transmitting belt comprising a tension resisting core having at least three longitudinal rows of apertures, the width of 85 the apertures of the median row being equal to the sum of the widths of the sidelong apertures, at least two strips of yielding material laced entirely around the belt through 90 said apertures, one of said strips being wound in an helical manner around the longitudinal portion of core limited by the median row and one sidelong row, and the other wound around the other longitudinal portion defined by the median row and the other sidelong 95 row.

In testimony whereof I have signed my name to this specification.
